Patented July 26, 1921.

UNITED STATES PATENT OFFICE.

CHRISTOPHER DEVENISH, OF BOSSBURG, WASHINGTON.

MINER'S DRILL-HOLDER.

1,385,523.

Specification of Letters Patent. Patented July 26, 1921.

Application filed April 24, 1920. Serial No. 376,342.

To all whom it may concern:

Be it known that I, CHRISTOPHER DEVENISH, a citizen of the United States, residing at Bossburg, in the county of Stevens and State of Washington, have invented new and useful Improvements in Miners' Drill-Holders, of which the following is a specification.

The object of this invention is to provide a device for holding miners' drills during the sharpening operation thereof.

A miner has a set of working drills all of the same diameter but of different lengths. These drills are successively used in the operation of drilling to different depths and all of the drills of a set are of the same shank diameter so that they will fit a single power machine. The drilling ends of miners' drills are sharpened by first heating the same, or rather the drilling ends thereof, and then applying to said drilling ends a sharpening die to the latter of which hammering blows are applied which exert an endwise thrust on the drill. Because of the fact that the drills are sharpened a good many times during their lives they become somewhat shortened in length with respect to their initial length when new. Thus the proposition of devising an efficient holder for drills of this character involves the problem of not only accommodating the device to a set of drills of a rather wide range of initial length, but also taking into account the lesser variation of length which results from repeated sharpening operations. The drill must be held at a point adjacent its drilling end as well as being supported against the longitudinal thrust from the hammer sharpening blows, and irrespective of the variation of length of the drill, the means for holding or stabilizing the drill shank near the drilling end must always be below said end.

It is one of the features of my invention to provide mechanism which may be lengthened or shortened in accordance with the length of drill to be sharpened, said mechanism preferably being divided into supporting units, two or more of which may be disposed in superimposed relation with respect to each other, or one of which may be superimposed upon the base of the device in such a manner that irrespective of

the height of the supporting units employed, the hammering thrust will be transmitted lengthwise thereof to the supporting base.

A further feature consists in employing individual supporting units which are movably mounted in such a manner that they can be selectively adjusted into and out of superimposed relation to the base and each other for the purpose of sustaining the particular length of drill to be sharpened.

A further feature consists in providing the supporting units or drill supporters with interlocking parts so that they will be held in vertical aligned relation after they have been adjusted into an operative position.

The invention has many other objects and features which will be more fully described in connection with the accompanying drawing and which will be more particularly pointed out in and by the appended claims.

In the drawing:

Figure 1 is a view in side elevation, with parts in section, illustrating most improved form of my invention.

Fig. 2 is a sectional view on line 2—2 of Fig. 1.

Fig. 3 is a view looking in the direction of the arrow of Fig. 1.

Like characters of reference designate similar parts throughout the different figures of the drawing.

As illustrated, 1 designates a supporting base on which is mounted an upright 2. A shank holder 3 is secured to the upper end of the upright 2, as shown. For a purpose which will later appear, the base 1 is provided with an anvil portion 4 which is preferably removably mounted in a socketed portion 5 of the base 1, not only for purposes of facilitating removal and renewal of the anvil portion but also to avoid making the entire base 1 of a material suitable for the anvil 4. The anvil 4 may be secured by screws 6 and the same is shown as being provided with a socket 7 of a predetermined depth below the upper surface 8, or rather that portion thereof immediately surrounding the socket 7.

A plurality of drill supporters or supporting units is indicated at 9, 10, 11 and 12, the number of which may be increased or decreased in accordance with the working re-

uirements without in any way affecting the manner of their operation or my invention. As shown, each supporter is provided on its upper end with a socket as indicated at 5 13 to 16. The lower end of each unit terminates and is reduced to form tenons as indicated at 17 to 20, the tenon of one unit fitting into the socket of the next lower adjacent unit, except in the case of the lower- 10 most unit 9 whose tenon 17 fits into the socket 7 of the anvil 4. The upper socket 16, or in any event the socket of the upper- most unit, will function to receive the lower end of the shank 21 of the drill and it is 15 a feature of my invention to proportion these sockets to receive the end of the drill shank. Thus it will be seen that the tenons and sockets serve to lock the units 9 to 12 in their alined and superimposed relation so 20 that they will function much the same as an integral rod in transmitting the hammering stresses direct to the anvil 4.

Reference will next be made to the specific manner shown whereby the supporting units may be adjusted selectively into and out of operative positions. The units have arms 22 to 25, preferably rigidly secured thereto. The remaining ends of the arms are pivoted at 26 to 29 to collars 30 to 33, all of 30 which are identical in form and operation and only one of which need be described in detail. I prefer to form these collars of a strip of metal the ends 34 of which are held in spaced relation by a spacing block 35 to 35 which the ends are secured. The upright 2 is recessed at 37 so that the strap will encircle the upright between opposing shoulders. The arms extend between the free ends 34 and a stop pin 38 serves to limit downward 40 movement of the arms beyond the horizontal position shown so that when the arms are swung out of superimposed relation, as shown in Fig. 2, they will be horizontally supported and substantially in position to 45 be swung into operative relation. The pivotal connection described permits of each unit being elevated sufficiently to insert its tenon in the next lower socket of either the base or the subjacent unit. Now it will be 50 seen that practically no strain is imposed upon the arms nor upon their collar connection with the upright 2.

The holder 3 has a recess 39 into which the shank 21 seats or is inserted. A retainer 40, 55 pivoted at 41, and movable into recessed portions 42 and 43, serves to retain the shank 21 in the holder 3. Thus considering that the drill 21 is a new drill, and of the shortest length, it will be seen that even after the 60 length of this drill has been reduced by repeated sharpening operations, the parts are so proportioned that the holder 3 will always be well below the drilling end 44. Proportionately, the remainder of the units are 65 likewise arranged for drills of successively

greater length. No strain is imposed upon the holder 3 and the latter functions primarily to stabilize the upper end of the drill.

The preferred operative use of my im- 70 proved device may be described as follows:-

Assuming that a set of miners' drills comprised four drills, then the user would start with the longest drill to be sharpened and 75 would swing aside units 12, 11 and 10 after the manner shown in Fig. 2, thereby leaving the socket 13 free to receive the lower end of such longest drill. The drilling end thereof would be inserted in the holder 3 as 80 shown in Fig. 1. Of course the drilling end would be first heated. Then the die is placed upon the drilling end and a succession of hammer blows will serve to sharpen said end, all of the hammering thrust being 85 transmitted through the unit 9 to the anvil 4 and base 1. After sharpening the longest drill the next unit 10 will be swung into position, the same being lifted slightly to insert its tenon 18 into the socket 13. This opera- 90 tion will continue down to the shortest drill. If desired, the socket 7 in the anvil 4 may be utilized for the longest drill thereby reducing the number of units per set of drills, 95 by one unit.

These hammering blows are not exceptionally heavy and of course they are imparted with a very sudden impact so that if the units are made of sufficient strength, they cannot buckle and will to all intents and 100 purposes act as a single rod. Thus it will be seen that these units may be broadly termed a mechanism which may be lengthened or shortened to accommodate miners' drills of different lengths.

It is believed that my invention will be fully understood from the foregoing description, and while I have herein shown and described one specific form of my invention, I do not wish to be limited thereto except 110 for such limitations as the claims may impart.

I claim:

1. In a device for supporting miner's drills of the same diameter and of different lengths for sharpening purposes, a frame including a base, a holder on said frame for the shank of the drill near the drilling end to be sharpened, and a plurality of supporters for supporting the remaining ends of drills of different length and transmitting the hammer sharpening thrust to the base, said supporters being selectively adjustable out of or into operative position for supporting drills of different length.

2. In a device for supporting miner's drills of the same diameter and different lengths for sharpening purposes, a base, and a plurality of supporters for selective super-imposition upon each other and the base with 130

the uppermost unit supporting the lower end of the drill to take the hammer sharpening thrust.

3. In a device for supporting miner's drills 5 of the same diameter and different lengths for sharpening purposes, a frame including a base and an upright, a holder on said upright for engaging the shank of the drill near the drilling end thereof, a plurality of 10 arms, a collar pivoted to each arm and each collar being rotatively adjustable about said upright as an axis, a supporting unit secured to each arm and each supporting unit having a socket on its upper end and a tenon 15 on its lower end for interlocking relation whereby the units may be selectively ad-

justed and locked into aligned relation, said base having a socket for the tenon of the lowermost unit.

4. In a device for supporting miner's 20 drills of the same diameter and different lengths for sharpening purposes, a frame including a base having a removable anvil provided with a socket, and a plurality of 25 drill supporting units adapted to be selectively arranged in superimposed relation in greater or lesser number upon said anvil to accommodate drills of different lengths.

In testimony that I claim the foregoing as my own, I hereby affix my signature.

CHRISTOPHER DEVENISH.
